UNITED STATES PATENT OFFICE

165,830

COMBINATION COOKY JAR AND BANK

Louis H. Dworkin, Philadelphia, Pa.

Application October 1, 1951, Serial No. 16,803

Term of patent 7 years

(Cl. D58—25)

To all whom it may concern:

Be it known that I, Louis H. Dworkin, a citizen of the United States, residing at 1463 Devereaux Avenue, in the city and county of Philadelphia, Commonwealth of Pennsylvania, have invented a new, original, and ornamental Design for a Combination Cookie Jar and Bank, of which the following is a specification, reference being had to the accompanying drawings, forming part thereof.

I claim:

The ornamental design for a combination cookie jar and bank, substantially as shown.

LOUIS H. DWORKEIN.
